UNITED STATES PATENT OFFICE.

LOUIS J. MILKE, OF BALTIMORE, MARYLAND.

AUTOMATIC CONTROL DEVICE FOR ELEVATORS.

957,077.

Specification of Letters Patent.

Patented May 3, 1910.

Application filed January 29, 1909. Serial No. 475,054.

To all whom it may concern:

Be it known that I, LOUIS J. MILKE, a citizen of the United States, residing at Baltimore city, State of Maryland, have 5 invented certain new and useful Improvements in Automatic Control Devices for Elevators, of which the following is a specification.

My invention has reference to safety appliances for electrically operated elevators and the like, and its object is to provide means whereby the elevator hoisting mechanism is rendered inoperative when any one of the several doors opening to the elevator 15 shaft is open, this effect being accomplished through the medium of a series of switches constituting circuit breakers in the hoisting and lowering power circuits of the elevator. The said switches are operated in one direction 20 by means of a solenoid which is located on a local circuit and is energized thereby, such energization being controlled by a series of circuit breakers located in the said local line. The plug member of each circuit 25 breaker is located on a door adjacent thereto, so that on the first opening movement of the door the circuit will be broken.

Another feature of my invention resides in the fact that should the door be opened 30 and the operator inadvertently move the controller lever to the full speed position and then close the door, the power will be gradually cut in just as if applied in the usual manner by the controller, thus preventing undue strain on the mechanism or 35 burning out of the armature.

The invention will be better understood from the following description taken in connection with the accompanying drawing in 40 which like characters of reference are used throughout the several figures, in which drawings—

Figure 1 is a view in elevation of an elevator equipped with my invention, the 45 same being schematically shown: Fig. 2 is an elevation partly in section of a portion of the mechanism shown in Fig. 1, the same being drawn to a larger scale, and Fig. 3 is a section on the line A, B, of Fig. 2.

Referring to Fig. 1, there is shown at C an elevator shaft door partially open, and at 50 D one in the closed position. Located on each of the said doors, at a convenient point as indicated at 1, is a block of conducting 55 material insulated from the door as indicated and serving when the door is closed

to make contact with two terminals 2 and 3, secured at a point adjacent to the door and in the path of the block 1.

A conductor 4 diagrammatically shown 60 leads from one of the contacts 3 to the winding of a solenoid coil 5.

From the contact 2 a conductor 6 leads to the next adjacent contact 3, and although only two doors, and but two sets of circuit 65 breakers are shown in the drawings, it is to be understood that any number of contacts 2 and 3 corresponding to the number of doors and located adjacent thereto may be connected in series, and from the last a 70 conductor 7 leads to a battery 8, and thence to the solenoid coil 5.

The solenoid 5 is secured to a U shaped bracket 9 which in turn is secured to a base 10 from which rises a boss 11 having a 75 through hole 12, square in cross section and into which is fitted a likewise shaped slide rod 13. Secured thereto at spaced intervals and insulated therefrom as shown at 14, are a number of knife blade contact members 15, 80 adapted to engage between spring contacts 16, arranged in the path of said members 15, the members 16 being one set of terminals for the different circuits constituting the speed changing mechanism of the ele- 85 vator hoist, the said members 15 and 16 forming circuit breakers or switches in these circuits.

The members 16 are secured to a post 17 at spaced intervals, and insulated therefrom 90 as indicated at 18, and are provided with down-turned ends 19 of varying length for a purpose which will presently appear.

Binding posts 20 are provided for the attachment of the conductors 21, said conductors forming one lead from the switchboard or other source of current supply, through a controller 22 located in the car F, the circuit being completed through a conductor 23.

The upper end 24 of the slide rod 13 forms the core of the solenoid, and its extreme end 25 is formed into a piston head and is fitted into the spool 26 of the solenoid coil, thus forming a dash-pot. The speed at which 105 the core travels on its upward stroke is regulated by the escape of air through a V shaped slot cut in a set screw 27 fitted in a threaded opening at the top of the dashpot.

The solenoid core is provided with a central duct 28, opening to one side at its lower

100

110

end and opening into a cup-shaped chamber 29 in the upper end of said core 24, where it is closed during upward movement of said core by a ball valve 30.

5 The operation of the device is as follows: Observe Fig. 1 and let it be assumed that the operator desires to lower the car F, he closes the door, thereby plugging the gap between contacts 2 and 3 adjacent to the said door; 10 the local circuit is thus closed and the solenoid 5 energized. The armature core 24 responds to the attraction of the solenoid and moves upwardly, carrying with it the contact members 15, thereby closing the 15 breaks in the conductor 21. The operator may now proceed to cut in the current in the usual manner by the use of the controller lever 28 until the desired speed is attained. Again, assuming the door to be in the open 20 position, should the operator inadvertently move the controller lever, say to the highest speed position, and then close the door, a sudden rush of heavy current, as would otherwise occur, would not result, because as 25 hereinbefore stated, the terminals 19 are of different lengths, thus making the space between the terminals 19 and the switch members 15 of different length, and by observing Fig. 1, it will be seen that the least 30 space is between the members making the break in the circuit to the first point on the controller box; the space between the members 15 and 19 thus increases successively, so that the current is cut in just as if cut 35 in by the controller lever 28. The cutting in of these various circuits may be made as gradual as desired by the adjustment of the set screw 27. It being desired that the solenoid core shall descend quickly when 40 its circuit is broken, I provide for the same by the duct 28, which will freely admit air above the piston 25 of said core during the downward movement thereof. At the first opening movement of the door when the 45 desired floor is reached, the circuit passing through the solenoid is broken and the rod 13 is moved downwardly under the action of a spring 29 so that the circuit conductors 21 are broken and it will be impossible to 50 move the car until the door is again closed.

Slight changes and alterations might be resorted to in the form and arrangement of the several parts described, without departing from the spirit and scope of my invention, and hence I do not wish to limit myself to the exact construction as herein set forth; but

Having fully described my invention, what I claim as new and desire to secure by 60 Letters Patent, is:

1. A safety-mechanism for electrically-propelled elevators, comprising, in combination with an elevator-car, hoisting-and-lowering speed-changing circuits, having terminals, an armature-member carrying circuit-

make-and-break members disposed in proximity to said terminals, a solenoid adapted, when energized, to attract said armature-member and thereby to bring said circuit-make-and-break members into contact with 70 said terminals to complete the circuit, a circuit for energizing said solenoid, terminal-members in said circuit, and a member carried by the elevator-shaft door adapted to contact with said terminal-members, thus to 75 close the circuit when the door is closed and, vice-versa, to break the circuit when the door is open.

2. A safety-mechanism for electrically-propelled elevators, comprising, in combination with an elevator-car, hoisting-and-lowering speed-changing circuits, having terminals, an armature-member carrying circuit-make-and-break members disposed in proximity to said terminals, a solenoid adapted, 80 when energized, to attract said armature-member and thereby to bring said circuit-make-and-break members into contact with said terminals to complete the circuit, the upper portion of said armature-member being 85 formed as a piston and working in the central bore of said solenoid, a circuit for energizing said solenoid, terminal-members in said circuit, and a member carried by the elevator-shaft door adapted to contact with 90 said terminal-members, thus to close the circuit, when the door is closed, and, vice-versa, to break the circuit when the door is open.

3. A safety-mechanism for electrically-propelled elevators, comprising, in combination with an elevator-car, hoisting-and-lowering speed-changing circuits, having terminals, an armature-member carrying circuit-make-and-break members disposed in proximity to said terminals, a solenoid adapted, 100 when energized, to attract said armature-member and thereby to bring said circuit-make-and-break members into contact with said terminals to complete the circuit, perforated means closing the upper end of the 105 central bore of said solenoid, the upper portion of said armature-member being formed as a piston and working in the central bore of said solenoid, a circuit for energizing said solenoid, terminal-members in said circuit, and a member carried by the elevator-shaft door adapted, when the door is closed, to contact with said terminal-members, thus to 110 close the circuit, and, vice versa, when the door is open, to break the circuit.

4. A safety-mechanism for electrically-propelled elevators, comprising, in combination with an elevator-car, hoisting-and-lowering speed-changing circuits, having terminals, an armature-member carrying circuit-make-and-break members disposed in proximity to said terminals, a solenoid adapted, when energized, to attract said armature-member and thereby to bring said circuit-make-and-break members into contact with 115 120 125 130

5 said terminals to complete the circuit, means closing the upper end of the central bore of said solenoid, and comprising, in part, a set-screw having a V shaped slot, the upper portion of said armature-member being formed 10 as a piston and working in the central bore of said solenoid, a circuit for energizing said solenoid, terminal-members in said circuit, and a member carried by the elevator-shaft 15 door adapted, when the door is closed, to contact with said terminal-members, thus to close the circuit, and, vice versa, when the door is open, to break the circuit.

10 5. A safety - mechanism for electrically-propelled elevators, comprising, in combination 15 with an elevator-car, hoisting-and-lowering speed-changing circuits, having terminals, a vertically-disposed armature-member carrying horizontally - disposed, spaced circuit-make-and-break members disposed in proximity to said terminals and of differing lengths, a solenoid adapted, when energized, to attract said armature-member and thereby to bring said circuit-make-and-break members 20 into contact with said terminals to complete the circuit, a circuit for energizing said solenoid, terminal-members in said circuit, and a member carried by the elevator-shaft door adapted to contact with said 25 terminal-members, thus to close the circuit when the door is closed and, vice versa, to break the circuit when the door is opened.

30 6. A safety - mechanism for electrically-propelled elevators, comprising, in combination 35 with an elevator-car, hoisting-and-lowering speed-changing circuits, a vertical post, carrying spaced horizontally-disposed terminals for said speed-changing-circuits, a vertically-disposed armature-member carrying 40 horizontally-disposed, spaced circuit-make-and-break members disposed in proximity to

said terminals and of differing lengths, a solenoid adapted, when energized, to attract said armature-member and thereby to bring said circuit-make-and-break members into contact with said terminals to complete the circuit, a circuit for energizing said solenoid, terminal-members in said circuit, and a member carried by the elevator-shaft door adapted to contact with said terminal-members, thus to close the circuit when the door is closed and, vice versa, to break the circuit when the door is opened. 45 50

7. A safety - mechanism for electrically-propelled elevators, comprising, in combination 55 with an elevator-car, hoisting-and-lowering speed-changing circuits, a vertical post carrying spaced, horizontally-disposed terminals for said speed-changing circuits, said terminals having down-turned end-portions 60 of differing lengths, a vertically - disposed armature-member carrying horizontally-disposed, spaced circuit-make-and-break members disposed in proximity to said terminals and of differing lengths, a solenoid adapted, 65 when energized, to attract said armature-member and thereby to bring said circuit-make-and-break members into contact with said terminals to complete the circuit, a circuit for energizing said solenoid, terminal-members in said circuit, and a member carried by the elevator-shaft door adapted to contact with said terminal-members, thus to 70 close the circuit when the door is closed and, vice versa, to break the circuit when the door is opened. 75

In testimony whereof I affix my signature in presence of two witnesses.
